(57) **CLAIM**

The ornamental design for a baby carriage frame, as shown and described.

DESCRIPTION

FIG. 1 is a perspective view of a baby carriage frame showing my new design;

FIG. 2 is another perspective view thereof;

FIG. 3 is a folded perspective view thereof;

FIG. 4 is another folded perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is an enlarged view thereof; taken from the encircled portion 11 in FIG. 1 thereof;

FIG. 12 is an enlarged view thereof; taken from the encircled portion 12 in FIG. 1 thereof;

FIG. 13 is an enlarged view thereof; taken from the encircled portion 13 in FIG. 2 thereof; and,

FIG. 14 is an enlarged view thereof; taken from the encircled portion 14 in FIG. 2.

The dash-dash broken lines in the drawings depict portions of a baby carriage frame and form no part of the claimed design. The dash-dot-dash broken lines in the drawings are included to indicate a partially enlarged view and form no part of the claimed design.

1 Claim, 14 Drawing Sheets
